areas 9 in which the necessary identifying indicia may be entered.

From the foregoing description taken in connection with the accompanying drawing, it will be readily apparent to those skilled in the art that this invention provides an envelope or jacket especially well adapted for the storage and filing of phonograph record discs which must be protected against uneven or localized pressure on the opposite faces thereof, and at the same time must be supported against deformation by elevated temperatures; and that this invention achieves these purposes through the provision of an envelope in which each of the two side walls has uniform thickness through its entire area.

What I claim as my invention is:

A phonograph record jacket adapted to snugly receive a phonograph record therein through an open edge thereof comprising: a substantially square front wall of uniform thickness throughout its entire area and having straight edges and square corners; a two-ply back wall of uniform thickness throughout its entire area and of the same size and shape as said front wall and joined thereto along three complete marginal edges of the jacket, said two-ply back wall comprising flaps folded in from said three marginal edges of the front wall, one of the flaps being of the same size and shape as the front wall and comprising one entire ply of said two-ply back wall, and the remaining flaps together having an area equal to that of the front wall and being coplanar with their adjacent edges abutting so that together they form the other ply of said two-ply back wall;

and adhesive securing portions of the juxtaposed surfaces of the plys of the two-ply back wall together, said adhesive covering the unhinged marginal edge portions of the full sized flap and the portion thereof in juxtaposition to the abutting marginal portions of the other two flaps, the unjoined edges of the single ply front wall and the two-ply back wall being directly opposite each other and constituting the boundary of the open edge of the envelope through which the record is inserted and removed, so that the front wall as well as the back wall is of uniform thickness throughout the entire area of the envelope to assure against localized pressure upon a record in the jacket when such jacketed record is clamped between two parallel flat surfaces.

ALBERT J. FRANCK.
